US00D766752S

(12) **United States Design Patent** (10) **Patent No.:** **US D766,752 S**
(45) **Date of Patent:** ** *Sep. 20, 2016

(54) **WEARABLE DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/501,059**

(22) Filed: **Aug. 29, 2014**

Related U.S. Application Data

(63) Continuation of application No. 29/499,090, filed on Aug. 11, 2014.

(57) **CLAIM**

The ornamental design for a wearable device, as shown and described.

DESCRIPTION

FIG. 1 is a bottom front perspective view of a wearable device showing our new design; FIG. 2 is a top rear perspective view thereof;

FIG. 3 is a bottom view thereof;

FIG. 4 is a top view thereof;

FIG. 5 is a front view thereof;

FIG. 6 is a rear view thereof;

FIG. 7 is a right side view thereof; and,

FIG. 8 is a left side view thereof.

It is certified that error appears in the above-identified patent and that said Letters Patent is hereby corrected as shown below:

In The Specification

In the "Description" section, separate lines 1 – 3, "FIG. 1 is a bottom front perspective view of a wearable device showing our new design; FIG. 2 is a top rear perspective view thereof;" into two paragraphs and replace with

--"FIG. 1 is a bottom front perspective view of a wearable device showing our new design;
FIG. 2 is a top rear perspective view thereof;"--

Signed and Sealed this
Twenty-ninth Day of November, 2016

Michelle K. Lee
Director of the United States Patent and Trademark Office
